Victor J. Evans
ATTORNEY

Patented Dec. 16, 1924.

UNITED STATES PATENT OFFICE.

GERALD M. VAN DYKE, OF TIENSIN, CHINA, ASSIGNOR OF ONE-HALF TO FRED PRICE, OF FORT McDOWELL, CALIFORNIA.

PAPER FILE.

Application filed September 12, 1923. Serial No. 662,310.

To all whom it may concern:

Be it known that I, GERALD M. VAN DYKE, a citizen of the United States, residing at Tientsin, China, have invented new and useful Improvements in Paper Files, of which the following is a specification.

This invention relates to improvements in paper files of the type commonly employed for the retaining of letters, documents and like instruments in a flat bound condition.

The principal object of this invention is to provide a file of the above nature, which is of such a construction that one of the papers being held therein may be removed without affecting the remaining papers, irrespective of the position of the paper to be removed relative to the remainder of the group.

Another object is to provide means whereby all of the papers of the group may be readily secured together through the action of the file and later removed in a bound condition.

Another object is to provide a file which is simple in construction, convenient to use and one which may be manufactured at a reasonable cost.

Other objects and advantages will be apparent during the course of the following description.

In the accompanying drawings forming a part of this specification, and in which like numerals are employed to designate like parts throughout the same,

Figure 1 is a side elevation of my file in an extended position, the closed position being shown in dotted lines.

Figure 2 is an end elevation of my file in an extended position, and

Figure 3 is a fragmentary top plan view of my file.

Applicant is aware of the fact that various files have been employed for the purpose of retaining papers. These files, however, in most instances, comprised upwardly extending prongs upon which the papers were placed in succession, the result being that when a paper near the bottom was desired, the papers above the desired paper had to be removed.

I have overcome this difficulty by providing a top section similar to the bottom section, which top section is provided with telescoping tubes adapted to telescope the

ordinary pins, and I have slidably engaged the top section to the bottom section, with the result that the papers above the desired papers may be moved upwardly together with the top section, while the papers below the desired paper may be retained upon the bottom pins, after which the desired paper may be removed and the top section dropped to its normal position.

In the accompanying drawings wherein for the purpose of illustration is shown a preferred embodiment of my invention, the numeral 5 designates the base of the file, which is provided with a rearward extension 6. This extension serves to position an upright 7 having a rectangular cross section.

Positioned forward of this tubular member 7, are spaced pins as shown at 8 and 9. These pins are screw-threaded in the base 5. A circular depression as shown in dotted lines at 11 is provided around each of these pins, the purpose of which will be later seen.

At 12 I have shown a top section which is provided with a rearwardly extending portion 13 within which is positioned a rectangular tubular member 14, which tubular member is provided with a flared bottom as shown at 16, and is adapted to telescope the rectangular member 7. This tubular member 14 carries a latch 17 pivoted as at 18 and having a point which is adapted to pass through an opening 19 in the tubular member 14, and to engage a recess 10 formed in the rectangular member 7. This engagement is best shown in dotted lines in Figure 2.

It will be noted by viewing this figure that there are two recesses 10 formed in the rectangular member 7, one near the upper extremity and one near the lower extremity.

Mounted on the top section and spaced from this tubular member 14 are downwardly extending tubular members 21 and 22. These last-mentioned tubular members are positioned so as to telescope the pins 8 and 9 and are each provided with a pointed end as shown at 23 and 24.

Eyes as shown at 26 and 27 are provided in each of these tubular members near their points the purpose of which will be later seen.

The operation of my file is as follows:—

Assuming that a number of papers have been placed upon the pins 8 and 9 and that the top section is in the position shown in

Figure 1, the latch 17 is pressed, which releases its point from engagement in the recess 10 near the upper end of the member 7, thus allowing the top portion 12 to drop. 5 The result is that the pointed ends 23 and 24 of the tubular members 21 and 22 will pass through the papers upon the pins 8 and 9, during the telescoping action of this tubular member with respect to their pin.

10 The pointed ends will come to rest in the circular depression 11 and at the same time the latch 17 will engage the lower recess in the member 7.

15 We will now assume that it is desired to remove a paper from a point somewhere within the filed papers. The paper is located, the hand placed upon the paper and with the other hand the latch 17 is released and the top section 12 raised. At the same time 20 that the raising action takes place, the papers above the hand will travel upwardly with the tubular members 21 and 22 due to their friction and a clamping action, which occurs as soon as a slight sag occurs (which 25 action is well known).

When the upper section of the file has been raised to the full line position of Figure 1, the paper beneath the hand can then be raised and removed from the file and the 30 papers returned to their normal position.

It will thus be seen that I have provided a very simple file and one which will meet all of the requirements relative to a file of this nature.

35 By referring to Figure 2, I have shown in dotted lines a thread or string which may

be threaded through the eyes 26 and 27 while all of the papers are upon the pins 8 and 9. By now forcing the top portion downwardly, the ends of the string will be 40 threaded through the papers after which the ends may be tied and the papers may be transferred for storage.

It is to be understood that the form of my invention herewith shown and described 45 is to be taken as a preferred example of the same, and that various changes in the shape, size and arrangement of parts may be resorted to without departing from the spirit of the invention or the scope of the subjoined claim.

50 Having thus described my invention, I claim:—

In a device of the character described, a base, a rectangular member secured to said base and extending at right angles therefrom, a plurality of pins secured to said base, a circular recess formed in said base at a point surrounding each of said pins, a top member, a rectangular tubular member secured to said top member and adapted to telescope said first-mentioned tubular member, a latch secured to said tubular member and adapted to contact said rectangular member and a plurality of downwardly extending tubular members adapted to telescope said pins, said last-mentioned tubular members having eyes formed near the lower extremities thereof, substantially as and for the purpose specified.

70 In testimony whereof I affix my signature.
GERALD M. VAN DYKE.
